UNITED STATES PATENT OFFICE

PHILIP HUFELAND, OF NEW YORK, N. Y.

DESIGN FOR A MEMORANDUM-BOOK COVER.

SPECIFICATION forming part of Design No. 30,873, dated May 30, 1899.

Application filed May 6, 1899. Serial No. 715,870. Term of patent 3½ years.

To all whom it may concern:

Be it known that I, PHILIP HUFELAND, a citizen of the United States, residing at New York, borough of Manhattan, in the county of New York and State of New York, have invented and produced a new and original Design for a Memorandum-Book Cover, of which the following is a specification.

The feature of this design consists in the ornamental character of the cover, as set forth in the following specification and claim and illustrated in the annexed drawings, in which—

Figure 1 is a face view of a book-cover bearing and incorporating this design. Fig. 2 is a longitudinal section of the same along the line $x-x$, Fig. 1.

In the drawings are shown the lids 1 and 2 of the cover. The back to carry the lids is shown at 3. The hinges for the lids are

shown at 4. The lids have flat surfaces, and the outer surface of the lid 1 bears the ornamentation illustrated in Fig. 1. Said ornamentation consists of the ornamental line 5 in elliptical form, giving a medallion-like 25 appearance.

This design presents a novel, striking, and characteristic appearance.

What I claim as new, and desire to secure by Letters Patent, is— 30

The design for a memorandum-book cover, substantially as shown and described.

In testimony whereof I have hereunto set my hand in the presence of two subscribing witnesses.

PHILIP HUFELAND.
